UNITED STATES PATENT OFFICE

2,404,829

HELICOPTER

Clarence E. Darrow, Miami, Fla.

Application September 3, 1943, Serial No. 501,121

2 Claims. (Cl. 244—17)

1

The present invention relates to new and useful improvements in helicopters, and has for one of its important objects to provide a flying machine of this character comprising a unique arrangement of rotors driven in opposite directions through the medium of twin engines.

Another very important object of the invention is to provide a helicopter of the aforementioned character which embodies novel propulsion and control means.

Other objects of the invention are to provide a helicopter of the character described which will be comparatively simple in construction, strong, durable, reliable in operation, and which may be manufactured at low cost.

All of the foregoing, and still further objects and advantages of the invention, will become apparent from a study of the following specification, taken in connection with the accompanying drawing wherein like characters of reference designate corresponding parts throughout the several views, and wherein:

Figure 1 is a top plan view of a helicopter constructed in accordance with the present invention.

Figure 2 is a view in front elevation thereof.

Figure 3 is a view in side elevation of the machine.

Figure 4 is a fragmentary view in vertical longitudinal section, taken substantially on the line 4—4 of Figure 2.

Figure 5 is a view in side elevation of the elevator assembly.

Figure 6 is a top plan view of the rudder assembly with portions of the surfaces broken away in section, the elevator assembly shown in Figure 5 being omitted from the rear end of the fuselage.

Figure 7 is a fragmentary view in horizontal section showing, in top plan, the means for releasably securing the safety flaps in vertical or inoperative position.

Figure 8 is a view principally in horizontal section through the fuselage.

Figure 9 is a cross-sectional view through the forward portion of the fuselage.

Figure 10 is a view in horizontal section on an enlarged scale through the elevator assembly.

Referring now to the drawings in detail, it will be seen that the embodiment of the invention which has been illustrated comprises a fuselage of suitable dimensions and material which is designated generally by reference numeral 1. Landing wheels 2 are provided beneath the fuselage 1. The forward portion of the fuselage

2

1 comprises a cabin 3. The forward portion of the fuselage 1 further includes an anticinal top portion 4. Rising from the apex or peak of the top portion 4 of the fuselage 1 is a panel 5.

5 Mounted on the forward portion of the fuselage 1 is a frame structure 6. The frame structure 6 is transversely elongated and mounted for rotation in opposite directions on the ends thereof is a pair of rotors 7. Engines 8 in the fuselage 1 drive the rotors 7 in opposite directions by suitable means, such as shafts 9, universal joints 10, gears 11, et cetera.

15 Safety flaps 12 are hingedly suspended from the upper portion of the frame structure 6 on opposite sides of the fuselage 1. In the embodiment shown, the safety flaps 12 are releasably secured in vertical or inoperative position by means including shafts 13 which are journaled in bearings 14 on the frame structure 6 and which are operable from within the cabin 3. As 20 best seen in Figure 7 of the drawings, the shafts 13 have fixed thereon pairs of spaced fingers 15 which receive the flaps 12 therebetween for releasably securing said flaps against swinging movement and in vertical position.

25 Mounted on top of the frame structure 6, beneath the inner portions of the rotors 7, are pairs of inverted U frames 16. Series of slats 17 are journaled for vertical swinging adjustment between the pairs of frames 16 for receiving the air blast or wash from the rotors 7. Bars 18 are pivotally connected to the upper ends of the series of slats 17 for actuating said slats in unison. Cables 19 from hand levers 20 in the cabin 3 are connected to the ends of the bars 18 for adjusting the slats 17 as desired. Two such levers 20 are provided, one for each set or series of the slats 17.

30 Built into the fuselage 1 is a pair of wind tunnels 21. The tunnels 21 comprise, at their forward end portions, upwardly opening intakes 22 (see Fig. 9) on opposite sides of the anticinal top portion 4 of the fuselage 1. Thus, the tunnels 21 are adapted to receive the air blast or wash from the inner portions of the rotors 7. The upstanding panel 5 prevents air turrall between the rotors 7 and the oppositely inclined sides of the top portion 4 of the fuselage 1 direct the air into the intakes 22. At an intermediate point, the tunnels 21 merge into a single tunnel 23 (see Fig. 8) which extends to the rear end of the fuselage 1.

35 Mounted on the rear end of the fuselage 1 is an elevator assembly 24. The assembly 24 includes a pair of rearwardly projecting, substan-

tially U-shaped brackets 25 which are fixed on the upper portion of the fuselage 1. Journalized at an intermediate point for vertical swinging movement between the brackets 25 is a gang of elevators 26. A vertical bar 27 is pivotally mounted on the forward end portions of the elevators 26 for actuating same in unison. Cables 28 connect the bar 27 to a swinging column 29 in the cabin 3 for actuating the elevators 26.

Also mounted on the rear end of the fuselage 1, beneath the elevator assembly 24, is a rudder assembly 30. The assembly 30 includes a pair of substantially U-shaped brackets 31 which are mounted transversely on the rear end of the fuselage 1. Pivotally mounted for horizontal swinging movement on the brackets 31 and extending rearwardly therefrom is a gang of spaced, parallel rudders 32. A bar 33 is pivotally connected to the rudders 32 at intermediate points in said rudders for actuating same in unison. Cables 34 connect the bar 33 to the rotatable wheel 35 on the swinging column 29 in the cabin 3 for actuating the rudders 32.

It is thought that the operation of the machine will be readily apparent from a consideration of the foregoing. Briefly, the desired lift is had from the oppositely rotating rotors 7, said rotors being actuated by their respective engines 8. Forward or backward movement is had through the medium of the slats 17. With the slats 17 adjusted to the inclination shown in Figure 4 of the drawings, the wash or downward blast of air from the rotors 7 strikes said slats and drives the machine forwardly. The speed is governed by the inclination of the slats 17. With the slats 17 in a vertical position, the machine will ascend or descend vertically or hover. Rearward tilting of the slats 17 will cause the machine to travel backward. As the series of slats are adjustable independently, said slats may, if desired, be utilized to turn or assist in turning the machine. Air from the rotors 7 is directed into the intakes 22 of the tunnels 21 by the top portion 4 of the fuselage 1. The air thus is caused to enter the tunnels under pressure. This blast of air emerges at the rear end of the fuselage 1 and assists in propelling the machine forwardly. This air also strikes the surfaces 26 and 32 in a manner to materially increase the effectiveness thereof. Should one of the engines fail, that side of the machine will, of course, drop. When this occurs, the safety flaps 12 are released and said flaps swing upwardly to a horizontal position beneath the upper portion of the frame structure 6 where they are arrested and function as planes to assist the pilot in bringing the craft to a safe landing.

It is believed that the many advantages of a helicopter constructed in accordance with the present invention will be readily understood, and although a preferred embodiment of the machine is as illustrated and described, it is to be understood that changes in the details of construction and in the combination and arrangement of parts may be resorted to which will fall within the scope of the invention as claimed.

10. What is claimed is:

1. A helicopter comprising a fuselage including a forward part provided with an anticinal roof portion having a ridge extending longitudinally of said fuselage, a frame structure mounted on and extending laterally from opposite sides of the fuselage, rotors mounted on and disposed above said frame structure at opposite sides of the fuselage, means for actuating the rotors, a panel rising from and parallel with the ridge of the anticinal roof portion of the fuselage between the rotors, longitudinal air tunnels in the fuselage, said air tunnels including upturned intakes opening at their upper ends at opposite sides of the anticinal roof portion of the fuselage and below the inner portions of the rotors for receiving the air blasts therefrom, said tunnels opening through the rear end of the fuselage, and control surfaces mounted on said rear end of the fuselage for receiving the air from the tunnels.

2. A helicopter comprising a fuselage including a forward part provided with an anticinal roof portion having a ridge extending longitudinally of said fuselage, a frame structure mounted on and extending laterally from opposite sides of the fuselage, rotors mounted on and disposed above said frame structure at opposite sides of the fuselage, means for actuating the rotors, a panel rising from and parallel with the ridge of the anticinal roof portion of the fuselage between the rotors, longitudinal air tunnels in the fuselage, said air tunnels including upturned intakes opening at their upper ends at opposite sides of the anticinal roof portion of the fuselage and below the inner portions of the rotors for receiving the air blasts therefrom, said tunnels opening through the rear end of the fuselage, a series of transverse slats mounted for vertical swinging adjustment on the frame sections beneath the inner portion of each rotor and directly above said intakes for receiving the air blasts from said rotors, and means for actuating each series of said slats in unison.

CLARENCE E. DARROW.
